(57) **CLAIM**

The ornamental design for a solid state drive (SSD) enclosure for smartphone, as shown and described.

DESCRIPTION

FIG. 1 is a front, right, and top perspective view of a solid state drive (SSD) enclosure for smartphone showing our new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right, and top perspective view thereof, shown with an additional environmental subject matter; and, FIG. 10 another front, right, and top perspective view of FIG. 9, shown in an alternate configuration.

The broken lines in FIGS. 9 and 10 showing the docked smartphone depict environmental subject matter only and form no part of the claim; while all other broken lines depict portions of the solid state drive (SSD) enclosure for smartphone that form no part of the claimed design.
